CLAIM

We claim the ornamental design for an image drum cartridge, as shown and described.

DESCRIPTION

FIG. 1 is a top plan view of an image drum cartridge showing our new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a perspective view as seen from the top, front, and right side thereof; and,

FIG. 8 is a perspective view as seen from the top, front, and left side thereof.

The broken lines depict environmental subject matter only and form no part of the claimed design.
